CONTROL DEVICE

Chester S. Ingraham, East Aurora, N. Y., assignor to Sylvania Electric Products Inc., a corporation of Massachusetts

Application May 8, 1953, Serial No. 353,728

5 Claims. (Cl. 201—55)

This invention relates to a control device involving a potentiometer, a switch and a control shaft passing through the potentiometer and switch to operate other instrumentalities such as a variable tuning condenser, permeability tuner, or a second potentiometer.

Prior art devices of this character have been bulky and complex because the through shaft requires the switch of the combination to be offset from the shaft axis. This invention, by reason of the novel switch construction and by reason of the configuration of the switch structure relative to the remaining portions of the control device overcomes these objections of the prior art constructions.

It is therefore an object of this invention to make a small compact unit having the three functions of operating a switch, operating a potentiometer and operating a third device.

It is a further object of this invention to provide a switch whose parts shall surround a substantially central control shaft.

It is a still further object of this invention to provide a combined potentiometer and switch mechanism of which parts of each shall surround a substantially central control shaft.

Yet another object of this invention is to provide a novel switch that is especially adapted for use with an operating shaft for other instrumentalities, the shaft passing through the switch in a compact arrangement of switch and shaft.

Other objects can be ascertained after reading the following specification and claims when read in conjunction with the accompanying drawings in which

Fig. 1 is a longitudinal cross-section through a combined potentiometer, switch and control shaft, the control shaft being shown in side elevation.

Fig. 2 is a rear view of the combined unit showing the switch arrangement, and

Fig. 3 is an exploded view of the unit showing its component parts in perspective.

Referring to the figures more in detail, there is illustrated a housing comprised of an oval back plate 10, a wall 12, oval in cross-section, secured to the back plate, a cylindrical wall 14 secured to the first wall 12 and an insulating front plate 16 engaged by said cylindrical wall. A slotted partition plate 18 which may be made integral with the wall 12 forms two chambers in the unit, one to house the potentiometer and the other to house the switch. The back plate, the front plate and the partition wall are all centrally apertured to receive an operating shaft 20 for a third instrumentality, as will be described more in detail hereinafter.

The cylindrical wall may be secured to the oval wall 12 by spot welding or other well known means. The back plate 10 is secured to the oval wall 12 by means of lugs 22 extending from the edge of the wall and bent around the back of plate 10, some of the lugs lying in recessed portions 24 of the back plate to prevent sliding of the plate on the edge of the wall and others of the

2

lugs passing through holes 26 in the back plate. Similarly the front plate 16 is secured to the edge of cylindrical wall 14 by means of lugs 28 bent around the front of plate 16 and lying in recesses 30 in the plate.

5 Rigidly mounted in the insulating front plate is an externally threaded bushing 32, adapted to pass through a mounting hole in a chassis wall and adapted to have a lock nut threaded thereon to secure the unit in place. The plate 16 is generally circular in plan but there is an arcuate extension providing four tooth portions 34 with three intermediate recesses to snugly accommodate potentiometer terminal members 36. The outside terminal members are respectively connected to two opposite ends of an interrupted annular disc 38 having a carbon resistor surface, the disc and terminal members being secured to the insulating plate 16 by rivets 40 or the like. Cooperating with the resistance coated disc is a rotatable contact plate 42 having, for the sake of securing better electrical contact with the disc, a pair of spring fingers 44 engaging the resistance face of the disc 38. The circuit is completed to the middle terminal 36 of the potentiometer, secured to the insulating plate by a rivet, by means of a stationary contact ring 46 in sliding contact with the plate 42 and conveniently formed of stiff spring wire surrounding a flange 47 on the plate 42, this contact ring having a terminal portion 48 electrically joined to the middle terminal 36. The contact ring 46 and the rotatable plate 42 surround in noncontacting relation a hollow potentiometer and switch drive shaft 20 15 25 30 35 40 45 50 55 60 65 70 75 80 85 90 95 100 105 110 115 120 having its other end resting in a hole 91 in an extension of the partition wall. The partition wall is furthermore arcuately slotted as shown at 92 to enable the arms 84 to project into the housing portion in which the lug 78 operates and to be engaged by said lug in the rotation of the arm 60. The crank arm is conveniently formed of a single sheet of blank material bent to form the arms 84 and a saddle with slotted portion 93, shown in dotted lines in Fig. 3, and with a reentrant slot 94. Retained by the slotted portion and the reentrant slot is a fiber block 95, the upper edge of which has a central tongue 96 which, as shown in Fig. 2, pivotally engages with the lower end of a C-shaped spring 97 made of flat stock and stressed to its arcuate form by entering into a rectangular slot 98 in the lower end of the spring. The upper end of the spring is provided with a slot 100 similar in shape to the slot 98, pivotally engaging a tongue 102 of a spring leaf 104, said leaf spring carrying a contact member 106. The leaf spring is further provided with a right angularly bent portion 108 adapted to be fastened, as by a rivet 110, to an angularly bent saddle 112 in turn fastened to the back plate 10 by a rivet 114 passing through a hole 116 in the back plate. The saddle also has an abutment finger 118 positioned in the path of movement of the leaf spring to prevent the lower end of the spring leaf from being driven too far to the right, as seen in Fig. 2, and thereby to prevent possible disengagement of the C-shaped spring 97 from the leaf spring 104. The back plate also has mounted on it a fixed contact 120 mounted on an angular bracket 122 and fastened in position on the plate 10 by a rivet 124 passing through a hole 126 in the plate. The leaf spring is biased to normally urge the contacts 106 and 120 into engagement. The bracket 122 has a backwardly extending short finger 128 fitting in a hole 130 in the back plate to prevent rotation of the contact and, in the lower left hand side of the vertical flange of the saddle 112 there is provided with a backwardly extending finger to engage in a hole 132 in the plate 10 to prevent rotation of the saddle. The rivets 114 and 124 also serve to mount a pair of switch terminals 134 on the back plate, these too being provided with short fingers to engage in the holes 130 and 132 of the plate 10 to prevent rotation thereof.

From the above description it will be clear that operation of the hollow shaft 50 will rotate the plate 60 via the bifurcations 56 on the shaft thereby causing the lug 78 on the plate to engage one of the arms 84 on the crank arm 86 and through the fiber block 95 and C-shaped spring 97 operate the spring leaf 104. Also the rotation of the plate 60 will cause its projection 66 to rotate the washer 64 and through it the contact plate 42 with its fingers operating over the resistor 38.

At the same time without interfering with the operation of the switch or potentiometer, the through shaft 20 may be operated to control another element.

This shaft extends centrally through the entire organization thus far described and on to some instrumentality mounted in the chassis or on back of the control unit to be operated by the shaft. The instrumentality, as pointed out heretofore, may be a tuner of some character such as a tuner having an adjustable condenser or adjustable permeable member or it may be another potentiometer. The front ends of the control shaft 50 and of the operating shaft 20 may have nested or superimposed operating knobs mounted thereon to provide ready means for operating all of the units controlled by the shafts. The shaft 20, it will be noted, passes through the hollow shaft 50 as well as past the inner area of the C-shaped spring 97. The spring is so shaped and so mounted that in its movement it never contacts the shaft 20 and yet it serves to transmit forces from crank arm 86 to the leaf spring by reason of the connections at 98 and 100. The forces are carried around the shaft 20. The virtual line of thrust is, however, through the

shaft 20 and it shifts from a position in which the switch contacts are closed by reason mainly of spring leaf bias, to one overcoming the bias of the spring so as to effect separation of the contacts. As the block 95 is rotated the spring is first compressed by reason of points 96 and 102 being brought closer together and then released from pressure to allow parts to snap to their final positions. This method of transmitting forces around the shaft is effective in moving the movable contact and yet permits a compact arrangement of parts not only as to the switch itself but as to the combination of switch and potentiometer.

It will be obvious that various details of the organization may be varied without departing from the spirit of my invention, as defined in the following claims.

What is claimed is:

1. A control device including a casing having at least two parallel walls with aligned apertures, a shaft traversing said casing and passing through the aligned apertures, a pair of contacts within said casing one of which is movable and mounted on a leaf spring extending toward the shaft, an operating member in said casing, said pair of contacts and operating member being diametrically positioned with respect to said shaft, and means including a bowed force transmitting member partially encompassing the shaft and interconnecting the movable contact with the operating member.

2. A control device including a casing having at least two parallel walls with aligned apertures in said walls, a shaft traversing said casing and passing through the aligned apertures, a pair of cooperating contacts within said casing one of which is mounted on a flat leaf having a free end extending toward the shaft, an operating means for said leaf including a pivoted member, the free end of which extends toward said shaft, said flat leaf and pivoted member being on substantially diametrically opposite sides of the shaft, and a bow shaped spring member pivotally connected to both the free end of the flat leaf and the free end of the pivoted member and partially encompassing the shaft.

3. A control device comprising a casing structure having parallel front and back walls and a parallel partition wall dividing the casing into two chambers, a potentiometer in one of the chambers and a switch comprising contacts and operating means therefor in the other, means for operating said potentiometer and switch comprising in part a hollow shaft extending through the front wall and terminating short of the partition wall, the partition wall and back wall being provided with apertures in alignment with the hollow shaft, a control shaft extending through the hollow shaft, potentiometer chamber, and switch chamber and through the aligned apertures, the switch contacts lying to one side of the control shaft, displaceable means for operating the contacts on a diametrically opposite side of the shaft, and bowed force transmitting means interconnecting the displaceable means and one of the contacts to transmit motion from the former to the latter.

4. A control device including a casing having at least two parallel walls with aligned apertures through which an operating shaft may be passed, a pair of contacts within the casing to one side of the aligned apertures, a cantilever leaf spring mounting one of said contacts, with the free end of the spring extending toward the axis of the aligned apertures but terminating short of the apertures, an operating member in the casing on the other side of the axis of the apertures, a bowed force transmitting member bowed around the apertures to avoid passing across the openings and interconnecting the free end of the leaf spring with the operating member, and means coaxial with said apertures and extending through one of them to control the movement of said operating member.

5. A control device comprising a casing structure having parallel front and back walls and a parallel portion

wall dividing the casing into two chambers, a potentiometer in one of the chambers and a switch comprising contacts and operating means therefor in the other, means for operating said potentiometer and switch comprising in part a hollow shaft extending through the front wall and terminating short of the partition wall, the partition wall and back wall being provided with apertures in alignment with the hollow shaft, said apertures being provided to accommodate a central shaft adapted also to extend through the hollow shaft, potentiometer chamber and 10 switch chamber, the switch contacts lying to one side of the apertures, displaceable means for operating the contacts lying wholly on a diametrically opposite side of the apertures, and bowed force transmitting means inter-

connecting the displaceable means and one of the contacts to transmit motion from the former to the latter.
